UNITED STATES PATENT OFFICE

CHARLOTTE STANLEY, OF DETROIT, MICHIGAN

SOAP CONTAINER

Application filed May 6, 1927. Serial No. 189,252.

This invention relates to improvements in soap containers. It is an object of the invention to provide a simple and convenient form of soap container that may be carried by a lady in her bag or pocket, or by a gentleman, so that powdered soap of any desired variety may be available at all times either when travelling, when at work, or about town.

Another object of the invention is to provide a soap container having a grating plate therein, so that a piece of soap may be quickly and easily reduced to substantially powdered form, and also to provide an outlet through the container, normally closed by a closure member, through which powdered soap may be obtained from the container when required.

A further object of the invention is to provide a soap container in an attractive form so that it will be as ornamental as any other toilet article, and so simply constructed that it may be manufactured and sold at a reasonable price.

With these and other objects in view the invention, which consists in certain novel construction and combination of parts is hereinafter more fully described with the aid of the accompanying drawings, in which:

Figure 1 illustrates a perspective view of the invention with the cover open, and

Figure 2 is a perspective view with the cover shut.

Figure 3 is a section on the line 3—3 of Figure 2.

Figure 4 is a partial vertical section showing a modified form of grating plate.

Referring to the drawings, 1 designates a container having a cover 2 thereon. The latter is usually mounted on the container by means of hinges 3 which are preferably partly secured to a rigid upper portion 4 integral with the container.

In the container a perforate grating plate 5 is provided which extends substantially over the whole of the inner surface of the container that is exposed when the cover is open. The grating plate may either consist of wire mesh, as shown in Figures 1 and 3, the margins of which are secured, as by welding to a frame 6 the sides of which fit snugly within the container; or else the grating plate 5 may have

holes 7 punched therethrough to present a roughened perforate surface, as shown in Figure 4, and be integral with the frame 6.

The upper margins 8 of the container sides are usually flexed inwardly to provide a bearing surface for the lower margins 2^a of the cover 2, and also to receive the frame 6 which extends downwards and rests on the bottom of the container. As shown in Figure 3 the sides of the frame 6 are cut to terminate at one end just beyond the inner end of the cover, and have extensions 6^a thereon which bear against one end of the container and hold the grating plate against longitudinal movement. A guide strip 8^a secured transversely over the opposed sides of the margins 8 adjacent to the rigid upper portion 4 of the container may be provided to hold that end of the grating plate from rising when the cover is open.

A suitable fastening means should be provided to hold the cover in closed position shown in Figure 1 in the form of a projection 9 on an upper margin 8 of the container which takes into a corresponding depression 9^a in one of the margins 2^a of the cover 2.

Through one end of the container, or through one of the sides if preferred, an outlet opening 10 is provided below the grating plate. This opening is preferably normally covered by a conventional closure member 11 which is normally held in closed position by a spring 12.

The cover is opened to fill the container. Filling is accomplished by rubbing a piece of soap a few times across the grating plate 5 whereupon substantially powdered soap falls into the body of the container. When soap is required for use the closure member is opened and a little shaken out into the user's hand.

While in the foregoing the preferred construction has been described and shown, it is understood that the invention is susceptible to such modifications as fall within the scope of the appended claims.

What I claim is:

1. A soap container having a cover hinged thereon, a removable perforate grating plate in said container, said plate extending over substantially the whole surface within said

container exposed when said cover is open, projections on the sides of said grating plate extending under the upper side of said container, the grating plate sides extending downwards and resting against the underside of said container, said container having an outlet opening therethrough under the perforate portion of said grating plate, and a closure member adapted to cover said opening.

2. In a soap container, the combination of a casing having an open top, a frame removably carried in the casing and of less length than the casing, a grating member carried by the frame and disposed adjacent the open top of the casing, extensions on the frame bearing against one end of the casing to prevent movement of the frame in the casing, a cover for the open top of the casing, one end of the casing provided with an opening for dispensing soap therefrom, and a closure for the opening.

3. In a soap container, the combination of a casing having an imperforate bottom, three imperforate sides, and an open top, a cover on said top, a grater carried in said casing adjacent to and substantially in a plane with said open top, said grating being held against movement in said casing, the fourth side of said casing having an opening therethrough for dispensing soap from said casing, a closure member over said opening, and spring means tending to hold said closure shut.

CHARLOTTE STANLEY.
